COMBINATION WATCH AND IDENTIFICATION TAG HOLDER

Harry Gibbons, Chicago, Ill., assignor of one-third to William Weinberg and one-third to Louis Zeinfeld, both of Chicago, Ill.

Application August 23, 1950, Serial No. 11,886

Term of patent 3½ years

(Cl. D42—8)

To all whom it may concern:

Be it known that I, Harry Gibbons, a citizen of the United States of America and resident of Chicago, in the county of Cook and State of Illinois, have invented a new, original, and ornamental Design for a Combination Watch and Identification Tag Holder, of which the following is a specification, reference being had to the accompanying drawings, forming a part thereof.

Fig. 1 is a plan view of the combination watch and identification tag holder, showing my new design, the hour markings and hands shown in broken lines in Fig. 1, being omitted from the other figures for convenience of illustration.

Fig. 2 is a side view thereof.

Fig. 3 is a bottom view thereof.

Fig. 4 is a view of one end thereof.

Fig. 5 is a view of the other end thereof.

Fig. 6 is a perspective view thereof, showing the cover in closed position.

Fig. 7 is a perspective view thereof, showing the cover in open position.

The essential features of my design are shown in full lines.

I claim:

The ornamental design for a combination watch and identification tag holder, substantially as shown and described.

HARRY GIBBONS.
